(57) CLAIM

The ornamental design for a panel for modular structures as shown and described.

DESCRIPTION

FIG. 1 is a perspective view of a panel for modular structures.

FIG. 2 is a front view of the panel for modular structures of FIG. 1.

FIG. 3 is a left-side view of the panel for modular structures of FIG. 1.

FIG. 4 is a right-side view of the panel for modular structures of FIG. 1.

FIG. 5 is a rear view of the panel for modular structures of FIG. 1.

FIG. 6 is a top view of the panel for modular structures of FIG. 1; and,

FIG. 7 is a bottom view of the panel for modular structures of FIG. 1.

In the drawings, the ornamental design that is claimed is shown in solid lines. The broken lines and areas within the broken lines form no part of the claimed designed.

1 Claim, 5 Drawing Sheets
